HERMETICALLY SEALED ELECTRICAL APPARATUS

Charles E. Smiley, Livingston, N. J.

Application April 18, 1952, Serial No. 283,148

3 Claims. (Cl. 339—89)

This invention relates to hermetically sealed electrical apparatus and devices for excluding moisture and the like, and particularly to such devices which employ plug-in replaceable components.

In certain electrical systems, such as airborne electronic equipment for example, it is desirable to hermetically seal as many of the electrical components as possible in order to obtain protection against moisture and changes in atmospheric pressure. It also is desirable that certain components, such as electronic tubes and other components requiring replacement, be readily replaceable, and yet be rigidly secured in their operating positions.

Accordingly, it is an object of the present invention to provide an electrical apparatus wherein all components are hermetically sealed.

Another object is to provide a hermetically sealed receptacle for plug-in electrical components.

A further object is to provide a receptacle for rigidly holding and securing replaceable electrical devices.

Still further objects will be apparent from the following specification and from the drawing, in which:

Figure 1 is a side elevational exterior view of a preferred embodiment of the invention.

Figure 2 is a cross-sectional view taken on the line 2—2 of Figure 1.

Figure 3 is a cross-sectional view taken on the line 3—3 of Figure 2 and showing internal construction of the preferred embodiment.

Figure 4 is a cross-sectional view taken on the line 4—4 of Figure 3.

Figure 5 is a side elevational view of an individual pin-gripping receptacle used in the preferred embodiment of the invention.

Figure 6 is a cross-sectional view taken on the line 6—6 of Figure 5.

Figure 7 is a side elevational view of a tightener tool positioned in temporary operating cooperation with the preferred embodiment of the invention, and

Figure 8 is a top plan view of the structure shown in Figure 7.

Referring to the several figures of the drawing, a housing 11, preferably of metal, encloses electrical components and connecting wires. A hermetically sealed receptacle 12 comprises a supporting base plate 13 which is hermetically attached to the housing 11 by means of solder 14 or the like. An electronic tube 16 or other plug-in device, is secured in place by the receptacle 12.

Now referring particularly to Figure 3, and to Figures 4, 5, and 6, the receptacle 12 comprises an annular threaded member 21 securely attached to or integral with the base plate 13. Terminal pins 22 are positioned to extend through appropriate openings in the base plate 13 and are hermetically secured and sealed thereto by means of insulative bushings 23 preferably of glass or ceramic material. Preferably, the bushings 23 do not extend above the top plane of the plate 13. The terminal pins 22 are preferably arranged in a circular manner and are respec-

2

tively aligned with connector pins of the plug-in device 16 as will hereinafter be described.

Pin receptacles 24 are respectively attached electrically and mechanically to the terminal pins 22, preferably in axial alignment therewith. A support disc 25 of insulative material is positioned between the base plate 13 and the pin receptacles 24, and contains openings 26 through which the terminal pins 22 extend. The openings 26 are smaller in diameter than the pin receptacles 24, the lower ends of which form shoulders which rest upon and are mechanically supported by the support disc 25, thereby reducing pressure or strain on the bushings 23, as will hereinafter be described in greater detail. The support disc 25 also functions as a positioning gage for the pin receptacles 24 during manufacturing of the receptacle 12.

Each pin receptacle 24 comprises an opening 27 adapted to receive connector pins 28 which extend from the plug-in device 16, and a plurality of slits 31 extending radially outwardly from the opening 27 and extending partially along the length of the pin receptacle from the top end thereof. The slits 31 provide jaws 32 which are adapted to engage the connector pins 28. An annular groove 33 may be provided on each pin receptacle 24 near the bottom ends of the slits 31 in order to give resiliency to the jaws 32. An annular bevel 34 is provided at the top end of each pin receptacle 24. Figures 5 and 6 clearly show details of the pin receptacles 24.

A compression disc or plate 36 is positioned over the top portions of the pin receptacles 24, and comprises a plurality of aligned openings 37 into which the top portions of the pin receptacles 24 project, the openings 37 being counter bored and beveled to conform to the beveled top ends 34 of the pin receptacles 24. Each connector pin 28 extends through an opening 37 when the plug-in device 16 is in place. The plug-in device 16 shown in the drawing has a base 38 known in the art as an "octal" base, and comprises a central aligning plug 39 extending therefrom. The connector pins 28 also extend from the base 38. A central opening 40 is provided in the compression disc 36 to receive the aligning plug 39.

A threaded tightening ring 41 is positioned on the annular threaded member 21, in threaded engagement therewith, and comprises a collar 42 which extends over and against part of the top portion of the compression disc 36. A shoulder 43 may be provided at the top outer edge of the compression disc 36 for engagement with the collar 42, so that the top surface of the tightening ring 41 will be substantially flush with the top surface of the compression disc 36. Notches 46 may be provided in the periphery of the tightening ring 41 at the top portion thereof, for engagement with a tightener tool as will be described hereinafter. The outer surface of the tightening ring 41 may be knurled, if desired, to facilitate manual gripping and turning thereof.

Electrical components 51 may be positioned within the housing 11 and connected by means of wires 52 to each other and to the terminal pins 22. One or more external terminal pins 53 are positioned to extend through suitable openings in the housing 11 and are hermetically and insulatively secured thereto by means of bushings 54 preferably of glass or ceramic material. The external terminal pins 53 are electrically connected to the components 51 or to the terminal pins 22 by means of wires 56. If desired, the plug-in device 16 may partially or entirely comprise a connector plug, thereby utilizing one or more of the pin receptacles 24 as external connections, and eliminating the need for the external connector pins 53.

Now referring to Figures 7 and 8, a tightener tool 61 is shown in its temporary position of engagement with the tightening ring 41. The tightener tool 61 preferably has a cylindrical shape with an inner diameter sufficiently

large so that the tool may be temporarily inserted over and around the plug-in device 16. Inwardly projecting tongues 62 are provided at an end of the tightener tool 61 and are so positioned and of such size and shape so as to fit into and engage the notches 46 in the tightening ring 41 when the tightener tool is utilized to turn and tighten the tightening ring 41. Alternatively, the tightening ring 41 may be provided with tongues extending radially or upwardly therefrom, and the tightener tool 61 may be provided with notches to engage these tongues. The tongues and notches may be referred to generically as engagement members.

To insert and secure the plug-in device 16 in the receptacle 12, the device 16 is placed so that the connector pins 28 thereof enter through the respective openings 37 in the compression disc 36 and enter into the openings 27 of the respective pin receptacles 24. In this position, the jaws 32 of the pin receptacles 24 preferably will resiliently engage against the respective connector pins 28. The tightening ring 41 is then turned, either by hand or by means of the tightener tool 61, so that it is screwed downwardly and the collar 42 thereof bears against the compression disc 36, forcing the compression disc downwardly against the beveled portions 34 of the pin receptacles 24, thereby urging the jaws 32 of the pin receptacles inwardly against the respective connector pins 28. The support disc 25 functions to support the pin receptacles 24 at the bottom ends thereof, thereby avoiding undue strain of the bushings 23. The connector pins 28 of the plug-in device 16 are now tightly gripped, electrically and mechanically, by the pin receptacles 24, and at the same time the plug-in device 16 and the electrical components 51 within the housing 11, are hermetically sealed.

It has been found that even if the pin receptacles 24, or the bevels 34 thereon, are not accurately machined or aligned, the jaws 32 of a sufficient number of them will be caused to compress against the connector pins 28 so as to achieve secure attachment of the plug-in device 16 in the receptacle 12. For the best electrical and mechanical results, the pin receptacles 24 should be of uniform size and shape, whereupon the support disc 25 will insure accurate leveling thereof, and all of the connector pins 28 will become tightly gripped by the respective pin receptacles 24.

To remove the plug-in device 16, the tightening ring 41 is turned, either by hand or by means of the tightener tool 61, so that it is screwed upwardly and the pressure on the compression disc 36 is relieved, whereupon the plug-in device 16 may be pulled out of the receptacle 12.

The plug-in device 16 may comprise a connector plug having wires or cables extending therefrom, in which case the tightener tool 61 may be provided with a longitudinal slit 66, or may be of semi-cylindrical shape, in order to slip over and around the cables. The tool 61 is particularly useful in "tight" places.

While a preferred embodiment of the invention has been shown and described, various modifications thereof will be apparent to those skilled in the art, which modifications are included within the scope of invention. The true scope of the invention is defined in the claims.

What is claimed is:

1. A hermetically sealed receptacle comprising a substantially flat base plate having a plurality of openings therethrough, a plurality of terminal pins positioned substantially perpendicular to said base plate and respectively extending through said openings and hermetically sealed to said base plate, a plurality of elongated pin receptacles each comprising an elongated member having a shoulder

at one end and a plurality of jaws at the other end thereof, said jaws having a beveled surface at said other end, said pin receptacles being substantially perpendicular to said base plate and respectively attached to said terminal pins on one side of said base plate with said shoulders fixedly spaced from said base plate and said other ends being relatively farther away from said base plate, an outside-threaded annular ring attached at an end thereof to said one side of said base plate and encircling said terminal pins, a support disc positioned within said annular threaded ring between and in engagement with said base plate and said shoulders and containing a plurality of openings through which said terminal pins extend, a circular compression plate positioned over the beveled surfaces of said jaws substantially parallel to said base plate and containing a plurality of beveled openings therethrough respectively positioned in engagement with the beveled surfaces of said jaws, and an inside-threaded annular tightening ring positioned in threaded engagement with said outside-threaded annular ring and encircling said compression plate and having an inwardly extending annular shoulder in engagement with a surface of said compression plate.

2. A receptacle as claimed in claim 1, in which said compression plate is provided with an annular recessed shoulder at the outer extremity of the surface thereof farthest from said base plate, said inwardly extending shoulder of said tightening ring being in engagement with said recessed shoulder.

3. A receptacle comprising a substantially flat base plate having a plurality of openings therethrough, a plurality of terminal pins positioned substantially perpendicular to said base plate and respectively extending through said openings, a plurality of elongated pin receptacles each comprising an elongated member having a plurality of jaws at an end thereof, said jaws having a beveled surface at said end of said elongated member, said pin receptacles being substantially perpendicular to said base plate and respectively attached to said terminal pins on one side of said base plate with said beveled surfaces being relatively farthest away from said base plate, an outside-threaded annular ring attached at an end thereof to said one side of said base plate and encircling said terminal pins, a circular compression plate positioned over the beveled surfaces of said jaws substantially parallel to said base plate and containing a plurality of beveled openings therethrough respectively positioned in engagement with the beveled surfaces of said jaws, and an inside-threaded annular tightening ring positioned in threaded engagement with said outside-threaded annular ring and encircling said compression plate and having an inwardly extending annular shoulder in engagement with a surface of said compression plate.
